COUPLER

Harry H. Wolfe, Columbus, Ohio, assignor to The Buckeye Steel Castings Company, Columbus, Ohio

Application March 17, 1949, Serial No. 81,893

5 Claims. (Cl. 213—144)

1

The present invention relates to a railway coupler of the knuckle type and the invention more particularly pertains to tightlock couplers and to improvements in the lock and associated parts of such coupling devices.

The tightlock coupler in present day use is provided with a lock having a wedge-shaped face which is adapted to be engaged by a surface on the knuckle tail which is inclined with respect to a vertical plane. Such inclined lock bearing surfaces facilitate movement of the lock to a locked position when the knuckle is closed. The wedge-shaped lock, however, has the disadvantage that when heavy pulling forces are applied on the knuckle a resultant force is developed by reason of the inclination of the lock bearing surfaces on the knuckle tail and the lock and this force is in a direction tending to lift the lock. In the use of a coupler having angularly disposed lock bearing surfaces train partings have occurred which may be partly attributed to the wedge type of lock. The tendency of the lock to move upwardly is more pronounced when the lock bearing surfaces are moist or oily.

An object of the present invention is to provide lock bearing surfaces between the knuckle and the lock with these surfaces disposed in a substantially true vertical position or substantially parallel to the axis of the knuckle pivot pin so as to avoid wedging action which tends to lift the lock towards an unlocked position.

A further object of the invention is to provide parts of a tightlock coupler with finished or machined surfaces which are shaped to provide a minimum of clearance between the lock engaging face of the knuckle and a vertical face on the lock to reduce slack in the contour of the coupler and at the same time provide a knuckle and lock assembly which will permit the lock to drop to the locked position.

A still further object of the invention is to provide guiding surfaces on the knuckle tail which bias the lock to a position for moving downwardly to the locked position even though the lock bearing surfaces are vertical with the clearance therebetween at a minimum and as small as one thirty-second of an inch.

Other objects and features of the invention will be more apparent to those skilled in the art as the present disclosure proceeds and upon consideration of the following detailed description and the accompanying drawings wherein an exemplary embodiment of the invention is disclosed.

In the drawings:

2

Fig. 1 is a sectional plan view of a coupler assembly exhibiting the invention.

Fig. 2 is a sectional elevation of the coupler organization looking towards the knuckle side of the coupler.

Fig. 3 is a fragmentary sectional view taken approximately on the line 3—3 of Fig. 1 showing the lock in a raised position with the knuckle partly open.

Fig. 4 is a transverse section taken generally on the line 4—4 of Fig. 1 showing the lock in the locked position.

Fig. 5 is a sectional view similar to Fig. 3 showing the lock in an intermediate position and the knuckle partly closed.

Fig. 6 is an elevational view of the guardarm side of the lock.

Fig. 7 is a front elevational view of the lock.

Fig. 8 is an elevational view of the knuckle side of the lock.

Fig. 9 is a plan view of the lock.

Fig. 10 is a sectional view taken on the line 10—10 of Fig. 4 and showing the position of the lock as the knuckle starts to move toward the closed position.

The invention is directed to a coupler provided with lock bearing surfaces arranged in a substantially vertical plane and approximately parallel with respect to the axis of swinging movement of the knuckle. Such lock bearing surfaces thereby provide a structure which avoids a tendency of the lock to be lifted when heavy loads are applied in pull on the coupler. The vertical lock bearing surfaces also prevent the lock from lifting or rising as a result of the presence of any liquid or lubricating materials on the knuckle and the lock. The invention further pertains to the structure of the knuckle and lock to promote downward movement of the lock when the knuckle is moved to the closed position and to maintain the lock in an elevated position when the knuckle is open. Another feature of the invention relates to the design of the lock and the knuckle tail appendage so that the movement of the knuckle to the closed position will prepare the lock for downward movement to the locked position even though the clearance between the bearing surfaces on the lock and the knuckle tail are as small as one thirty-second of an inch.

Referring to the drawings there is shown at 19 a coupler body or head. In the embodiment illustrated the coupler is of the tightlock type provided with aligning wings 12 and 14 on each side of the coupler head. The lug carried by the

guardarm side is adapted to enter a recess carried by a similar coupler and the mating coupler is also provided with a guardarm lug adapted to enter the recess provided in the aligning wing 14. These features of the coupler are well-known and do not form a part of the present invention. A knuckle 16 is carried by the coupler head in the usual manner which is adapted to turn about the axis of a knuckle pin 17. The knuckle 16 and the pin 17 are associated with conventional type knuckle pivot lugs on the coupler head. A support pin 18 is employed in the usual manner to maintain the knuckle pin 17 in place. The tail of the knuckle is illustrated at 19 and is generally of a construction like that of the prior art but the surfaces thereof for cooperation with the lock and the locking face as hereinafter described represent important changes over the known devices. The coupler includes a knuckle thrower 24 pivoted for swinging movement about the axis of its trunnion 22. The tip 20 of the thrower engages a shoulder 25 on the under side of the knuckle 16 for moving it to an open position.

The lock is shown generally at 23 and is mounted for vertical movement within the coupler body 10 which includes a lock housing 24 shown in Figs. 2, 3, 4 and 5. The lock 23 is actuated by means of lock lift assembly of a known type which includes a rotary lever 26 cooperating with a toggle 27. The lock 23 is provided with a leg 28 which depends into a lock leg cavity or opening 30 for connection to the toggle 27. For this purpose a lock trunnion 29 is provided which extends laterally from the lower end of the lock leg 28.

The knuckle tail 19 on the lock side is provided with a lock bearing face or surface 31 and this surface is arranged in a substantially vertical plane as best shown in Figs. 3, 4 and 5. This lock bearing face 31 is also substantially parallel to the axis of the knuckle pin 17. The face 31 is machined in contrast to the lock bearing surface of the Association of American Railroads Standard Type E coupler which is unmachined and therefore requires a considerable amount of clearance of the associated parts to permit the lock to move downward to the locked position. Immediately above the upper end of the vertical lock bearing face 31 the knuckle tail carries an inclined surface 32. This sloping surface 32 is arranged at a steep inclination and at an angle of approximately twenty degrees with respect to a vertical plane and with respect to the lock bearing face 31. The flat inclined surface 32 on the knuckle tail 19 merges at its upper end with a second inclined surface 33 provided immediately above the inclined surface 32. The surface 33 is inclined with respect to the vertical face 31 at about fifty degrees. The surfaces 32 and 33 are also machined and each carries a substantially straight flat finish. The knuckle tail 19 is provided with a further inclined surface 36 of relatively large area as shown in Figs. 1, 3, 4 and 5. The knuckle tail 19 also carries a bearing surface 38 which is adapted to engage a side wall or abutment surface 39 of the coupler head. The bearing surface 38 on the knuckle tail is machined and the surface 39 forming an adjacent portion of the inner wall of the coupler body is ground to very close relation to a lock bearing wall 40 on the coupler head and forming a part of the lock housing 24.

The lock 23 is provided with a flat and substantially vertically disposed knuckle engaging sur-

face 41. A surface 42 is provided on the lock immediately above the vertical surface 41. The surface 42 is inclined and so shaped that this side portion of the lock is substantially parallel to the surface 32 on the knuckle tail when the lock is in the locked position. A further inclined flat surface 43 is provided on the lock 23 and this surface is substantially parallel to the surface 33 on the knuckle tail when the knuckle is in the closed position and with the lock in the locked position shown in Fig. 4. These faces on the knuckle side of the lock 23 are machined to smooth flat surfaces. The lock 23 carries a ledge 46 under the lock fulcrum 45 which will ride on and engage a top surface 47 of the knuckle tail 19 when the knuckle is in an open position.

The lock includes a relatively flat side surface 48 which is adapted to engage the inner wall surface 49 of the lock housing 24. When the knuckle 16 is moved towards the closed position the ledge 46 of the lock 23 rides on the surface 47 on the knuckle tail 19. The lock while being thus maintained in the raised position is restrained from moving laterally with the knuckle tail 19 by bearing surfaces 51 and 52 provided within the lock housing 24 as shown in Fig. 10. These guiding surfaces 51 and 52 engage corresponding surfaces 54 and 55 on the lock. The guide surface 52 is provided on the inner edge of a vertically disposed rib 53. With the lock 23 engaging against the guide surfaces 51 and 52 there is a clearance of about one eighth of an inch between the face 48 of the lock and the guide wall 49. Thus the lock is shifted to the position shown in Fig. 10 as the knuckle is moved toward the closed position.

When the knuckle is open the lock 23 is supported in the raised position by the knuckle tail surface 41. As the knuckle is rotated towards the closed position the under side of the lock ledge 46 rides on the surface 47 of the knuckle tail and then slides down the inclined surface 36. The sloping surface 36 permits the lock to be moved downwardly so that a corner 60 of the lock then engages the surface 33 on the knuckle tail. When the surface 33 on the knuckle tail contacts the coupler head surface 39 the lock guiding surfaces 54 and 55 are in engagement with the lock housing 24 at 51 and 52 and the corner 60 of the lock 23 is partly down the steep inclined surface 32 on the knuckle tail as shown in Fig. 5. The lock 23 then shifts to the right from the position shown in Fig. 10 as the corner 60 moves downwardly on the inclined surface 32. The surface 48 of the lock then engages the inner surface 49 of the lock housing 24 as shown in Fig. 5. Due to the weight of the lock and its momentum in sliding from the surface 47 onto the surface 36 and down the surface 33 and downwardly on the inclined surface 32 the lock will drop to the locked position as shown in Fig. 4. If a clearance of at least one thirty-second of an inch is provided between the face 31 on the knuckle tail 19 and the surface 41 on the lock the coupler has been found to function properly and the lock moves into the locked position. The lock and the knuckle are so shaped that there is a small clearance between the surfaces 32 and 42 and between the surfaces 33 and 43 when the knuckle is closed and with the lock 23 in the locked position.

As hereinabove indicated the corner of the lock body 23 at the lower end of the vertical face 41 is arcuate shaped as indicated at 60 in Figs. 3, 5 and 7. It has been found that when the cou-

pler parts are formed as herein described the curvature at 60 should have a radius of a full one-fourth of an inch. This arcuate corner surface 60 engages the sloping surface 33 and the steeper inclined surface 32 and further promotes movement of the lock to the locked position.

In a conventional coupler provided with vertical locking faces on the knuckle and lock these surfaces have not been machined and do not have the steep inclined surface 32 on the knuckle tail. In such a coupler a clearance of one-fourth to three-eighths of an inch is necessary between the knuckle and the lock to obtain satisfactory locking. In such couplers there has been approximately three-fourths of an inch free slack in the contour. Therefore, the knuckle may be rotated rearwardly and take up the one-fourth to three-eighths inch clearance between the knuckle tail and the inner bearing surface of the coupler head to permit the lock to drop in the locked position.

In the standard tightlock coupler the knuckle thickness is the same as the opening in the contour and there has been no clearance between the knuckle tail and the side wall of the coupler head. Thus the clearance between the knuckle and the lock in the tightlock coupler when provided with vertical locking faces must be obtained by reducing the thickness of the lock or the knuckle tail which in turn loosens the contour. About one-half of the clearance between the knuckle and the lock is reflected in the looseness in the contour.

As distinguished from the standard type coupler and the conventional tightlock coupler the present invention provides guiding means for the lock so that with the knuckle in the fully closed position the lock engages an extra steep inclined surface 32 on the knuckle tail and drops to the locked position with only one thirty-second of an inch clearance between the vertical surface 31 on the knuckle tail and the vertical surface 41 on the lock and the coupler thereby provides a coupler assembly having only one sixty-fourth of an inch slack in the contour.

While the invention has been described with reference to specific structural features of the coupler and with regard to specific angular disposition of a number of faces of the lock and the knuckle, it will be understood that changes may be made in the details as well as the overall organization without departing from the spirit and scope of the invention as set forth in the appended claims.

What I claim and desire to secure by Letters Patent is:

1. In a railway car coupler, a coupler head, a knuckle swingably mounted on the coupler head, a rigid abutment surface on the coupler head at the knuckle side of the coupler, a tail portion on said knuckle adapted to engage said abutment surface in the closed position of the knuckle, a lock bearing face on the knuckle tail portion arranged in a substantially vertical plane, a flat inclined surface on the knuckle tail portion above and sloping away from an upper end of the lock bearing face at an angle of approximately twenty degrees, a second substantially flat surface on the knuckle tail portion above the first inclined surface merging with an upper end thereof and sloping away from the lock bearing face at an angle of approximately fifty degrees, a lock mounted for vertical movements in the coupler head, a knuckle bearing face on the lock arranged in a substantially vertical plane, an arcuate

corner on the lock at the lower end of said knuckle bearing face, means supporting the lock on the knuckle tail portion when the knuckle is in open positions, guide means engaged by a knuckle side of the lock during movement of the knuckle towards the closed position, said guide means being so located that the arcuate corner of the lock moves into engagement with said first inclined surface when the knuckle tail portion engages said abutment surface, a wall at a guard arm side of the lock, and the horizontal distance between said abutment surface and said wall being not more than one thirty-second of an inch greater than similar horizontal collective dimensions of the knuckle tail portion and the lock.

2. In a railway car coupler, a coupler head, a rigid abutment surface on the coupler head at the knuckle side thereof, a knuckle swingably mounted on the coupler head, a tail on said knuckle for engaging said abutment surface in the closed position of the knuckle, a lock bearing face on the knuckle tail arranged in a substantially vertical plane, a flat inclined surface on the knuckle tail portion sloping upwardly from an upper end of and away from the lock bearing face, a second flat surface on the knuckle tail portion merging with an upper end of the first inclined surface and sloping away from the lock bearing face at a greater angle than the inclination of the first inclined surface, a lock mounted for vertical movements in the coupler head, a knuckle bearing face on the lock arranged in a substantially vertical plane, a corner on the lock at the lower end of said knuckle bearing face, said lock being supported on the knuckle tail when the knuckle is in open position, guide means at the knuckle side of the lock engaged by the lock during movement of the knuckle towards the closed position, said guide means being so located that the corner on the lock is in vertical alignment with said first inclined surface when the knuckle tail engages said abutment surface, a guide wall at a guard arm side of the lock, and the horizontal distance between said abutment surface and said guide wall being approximately one thirty-second of an inch greater than similar horizontal collective dimensions of the knuckle tail and the lock.

3. In a railway car coupler, a coupler head, a non-yieldable abutment on the coupler head at the knuckle side of the coupler, a knuckle swingably mounted on the coupler head, a tail on said knuckle having a bearing surface for contacting said abutment in the closed position of the knuckle, a lock mounted for vertical movements in the coupler head, a knuckle bearing face on the lock arranged in a substantially vertical plane, a corner on the lock at the lower end of said knuckle bearing face, means including a horizontal surface on the knuckle tail supporting the lock in a raised position when the knuckle is in an open position, a lock bearing face on the knuckle tail arranged in a substantially vertical plane, an inclined surface on the knuckle tail sloping downwardly towards the lock bearing face from said horizontal surface, a flat inclined surface on the knuckle tail sloping downwardly from a lower end of the first inclined surface, a flat inclined surface on the knuckle tail sloping downwardly from the lower end of the second inclined surface and merging with an upper end of the lock bearing face, guide means engaged by the lock during movement of the knuckle towards the closed position, said guide means being so located that said corner of the

lock moves downwardly into engagement with said third inclined surface when the bearing surface on the knuckle tail contacts said abutment, a lock bearing wall at a guard arm side of the lock, and the horizontal distance between said abutment and said lock bearing wall being not more than a thirty second of an inch greater than similar horizontal collective dimensions of the knuckle tail portion and the lock.

4. In a knuckle for a railway car coupler, said knuckle having a knuckle pin opening therein, a tail portion on the knuckle, a lock bearing face on the knuckle tail portion arranged substantially parallel to the axis of the knuckle pin opening and in a substantially vertical plane when the knuckle is mounted on a coupler head, a flat surface on the knuckle tail portion above the lock bearing face merging with the upper end thereof and sloping away from the plane of the lock bearing face at an angle of approximately twenty degrees with respect thereto, and a second flat inclined surface on the knuckle tail portion above the first inclined surface merging with an upper end thereof and sloping away from the lock bearing face at an angle of approximately fifty degrees with respect to the lock bearing face. 20 25

5. In a knuckle for a railway car coupler, said knuckle having a knuckle pin opening therein, a tail on the knuckle, a lock bearing face on a lateral portion of the knuckle tail arranged substantially parallel to the axis of the knuckle pin opening and in a substantially vertical plane when the knuckle is mounted on a coupler head, a flat inclined surface on the knuckle tail above the lock bearing face merging with an upper end thereof and sloping away from the plane of the lock bearing face at a relatively steep angle, a second inclined surface on the knuckle tail above the first inclined surface merging with an upper end thereof and sloping away from the lock bearing face at an angle which is less than the slope angle of the first inclined surface.

HARRY H. WOLFE.
